[57] ABSTRACT

A releasable sheet holder including a body piece presenting a platen portion in two spaced-apart sections and a handle joining the sections and disposing them in a plane for supporting a flexible sheet, such as a cloth or a paper sheet. The two ends of the body piece are upturned, and the flexible sheet is lapped over the ends and a U-shaped clip slides over the ends for holding the sheet to the body piece. The body piece is made of a flexible material, and the two platen sections are spaced apart by the handle which can be squeezed together for tautly holding the sheet on the body piece when the handle portion is not being squeezed.

RELEASABLE SHEET HOLDER

This invention relates to a releasable sheet holder such as a sheet holder for holding a piece of cloth, a paper sheet, or the like, and doing so in a manner wherein the sheet is tautly held and is releasable for ready replacement of the sheet.

BACKGROUND OF THE INVENTION

The prior art is already aware of releasable sheet holders which receive and hold sheets, such as paper, cloth, and like materials. These sheets may be provided and utilized for the purpose of applying or spreading liquids on a surface, or for the purpose of holding a piece of sandpaper, or for any similar purpose. In the prior art holders, the constructions are generally complex in that they require spring-loaded retainers or clips or like complex fasteners for securing the sheet to a platen or body piece, or the prior art holders do not satisfactorily hold the sheet taut and snugly against a platen portion of the holder, or the prior art holders do not permit ready replacement of the sheets. Still further, the prior art holders do not receive and support a sheet so that the sheet can be readily positioned on the holder to overlap all of the ends and sides of the holder such that only the sheet itself is projected toward the working surface, such as for the purpose of spreading a liquid over the working surface by means of only the sheet, rather than the holder, or for the purpose of applying the sheet such as a sandpaper sheet, to the working surface without having the holder contact the working surface.

Accordingly, it is a primary object of this invention to improve upon the releasable sheet holders heretofore known. More specifically, it is an object of this invention to provide a releasable sheet holder which does not have the limitations or shortcomings as mentioned above, and, instead, the present invention provides a releasable sheet holder which readily and securely receives a sheet and holds and supports the sheet in a taut position for applying the sheet against the working surface, and to do this without exposing the holder itself to the working surface.

Still further, it is an object of this invention to provide a releasable sheet holder which is inexpensive to manufacture, is simple in its constructions so that there are no hinged or pivoted or other complex parts, but yet the sheet is releasably retained in a taut position on the holder.

Still further, it is an object of this invention to provide an inexpensive releasable sheet holder which is susceptible to a high speed type of mass production wherein the individual holder can be made from one continuous piece of a sheet form which can be extruded in a long length and from which the individual holders can simply be cut off at the desired length.

Still further, it is an object of this invention to provide a releasable sheet holder which yieldingly urges the sheet into a taut and snug position relative to the holder, but which nevertheless does not require any moving parts or any complex construction for achieving this objective.

Other objects and advantages will become apparent upon reading the following description in light of the accompanying drawings.

BRIEF DESCRIPTION OF THE DRAWINGS

FIG. 1 is an end elevational view of one embodiment of this invention and showing a sheet attached thereto.

FIG. 2 is a top plan view of a fragment of FIG. 1 with parts and the sheet removed therefrom.

FIG. 3 is a side elevational view of a fragment of FIG.

1.

FIG. 4 is a bottom plan view of a fragment of FIG. 1.

FIG. 5 is an end elevational view of another slightly different arrangement of the sheet holder shown in FIG. 1, and showing the central handle portion thereof.

FIG. 6 is a top plan view of a fragment of the holder shown in FIG. 1, and with the parts ready for assembly.

DETAILED DESCRIPTION OF THE PREFERRED EMBODIMENTS

The drawings show the holder includes the body piece, generally designated 10 and the two U-shaped clips, generally designated 11. A sheet 12 is shown to be releasably held by the holder, and it will be understood that the sheet may be of cloth, paper, or other material suitable for assuming the position shown in FIG. 1 such that the sheet has a planar central portion 13 and two end portions 14 and 16 which snugly overlap the upturned ends 17 and 18, respectively, of the body piece 10. Further, the sheet 12 is shown to have a face 19, and this face may be a nap of cloth material, such as fleece or the like, or it may even be a sandpaper face where the sheet 12 is of a sandpaper construction.

Thus the sheet 12 is tautly held by the holder which has a platen portion consisting of the two platen sections 21 and 22 which are shown to be disposed in the same flat plane and which have faces, such as the face 23, which present a backing to the planar portion 13 of the sheet 12. It will also be seen that the body piece 10 has an upstanding handle portion 24 which is centrally disposed on the holder and which actually forms a connection between the two platen sections 21 and 22.

Thus, as viewed endwise shown in FIG. 1, the body piece is shown to be generally of a W shape wherein the upturned ends 17 and 18 form the outer legs of the letter W, and the handle 24 forms the center portion or leg of the letter W. That is, all of the projections on the body piece 10 are to the side of the holder opposite from the side on which the sheet 12 is located, and thus no part of the holder is presented toward the working surface which would be in contact with the sheet surface 19, whether it be for the purpose of spreading a liquid or for sanding the working surface, or for any other purpose.

In further description of the holder as viewed in FIG. 1, it will be seen that the holder is made of one continuous sheet form extending from one upturned end 17 and through the platen section 21 and through the two handle legs or portions 26 and the handle spanning portion 27 and the platen portion 22 and into the other upturned end 18. In this configuration, the body piece 10 is of a simplified construction but yet it permits the secure holding of the sheet 12 and the ready replacement thereof, as hereinafter described. Still further, the holder can be made of an extruded plastic which is

somewhat flexible, as also hereinafter further described.

The drawings further show that the body piece 10 has its length extending in the direction along the terminal edges 28 of the upturned ends 17 and 18, and the handle 24 also extends in that direction and the ends 17 and 18 and the handle 24 extend throughout the length of the body piece 10 which extends from the edge 29 to the edge 31, as indicated by the dotted lines in FIG. 4. Thus the sheet 12 is shown to be of a length longer than the length of the body piece 10, and the sheet edges 32 and 33 extend beyond the respective edges 29 and 31 of the holder 10 to overlap the holder 10 and to avoid any part of the holder 10 being presented to or in contact with the working surface.

Again it will be noted that the sheet sides 14 and 16 wrap over the body piece upturned ends 17 and 18, and the clips 11 are snugly disposed over the sheet portions 14 and 16 for releasably holding the sheet 12 to the holder itself. The clips 11 are shown to be U-shaped, and FIG. 3 displays that the clips also extend throughout the length of the body piece 10, but again the sheet 12 extends beyond the edges of the clips 11, such as the edge designated 34 in FIG. 3. The clips 11 therefore have their legs 36 disposed slightly spaced apart but inwardly toward each other relative to the spanning portion 37 of the clips 11, and thus the legs 36 snugly hold the sheet 12 to the respective upturned ends 17 and 18. Also, the clips 11 are slightly flexible for yieldingly urging the sheet portions 14 and 16 in secure position relative to the upturned ends 17 and 18.

In generally W shape of the body piece 10, as shown and described, the body piece 10 can be made of one sheet form extending as shown and described and presenting the handle 24 in the loop shape shown. The body piece 10 can be made of a resilient material, and the platen sections 21 and 22 are shown spaced apart by the inter-connection of the handle portion 14 to have a space designated 38 therebetween. FIG. 5 shows that with the resilient characteristic of the handle 24, the handle portions designated 39 and 41 can be moved toward each other to come into abutment, as shown in FIG. 5, and thus the platen sections 21 and 22 can be moved toward each other at which time the sheet 12 can be applied to the body piece 10 and the clips 11 can be slid over the sheet portions 14 and 16, all for securing the sheet to the holder such that upon release of the squeezing of the handle 10 from the dotted position shown in FIG. 5 to the solid line position shown in FIG. 1, the sheet 12 will be automatically tautly held by the holder. Further, the arrangement is such that the user can readily and easily attach and remove the sheet 12 simply by placing one end of the sheet on the upturned end 17, for instance, and then squeezing the handle 24 with one hand and applying the other clip 11 to the upturned end 18 to hold the sheet 12 as shown in FIG. 1.

Further, it will be noticed that the terminal portions 42 of the upturned ends 17 and 18 are enlarged portions and thus the sheet 12 is securely held between the upturned ends 17 and 18 and the clips 11, and the clips 11 themselves are also held against sliding off the holder in a direction except that which is hereinafter described in connection with FIG. 6.

FIG. 6 shows the corner of the holder 10 with the sheet 12 applied thereto and with its sheet end 16 overlapping the leg 18 and with the clip 11 ready to be slid

axially of its length and onto the sheet portion 16. In this arrangement, the sheet portion designated 43 is crimped together, as shown in FIG. 6, and thus the clip can lead onto the sheet portion 16 for sliding as mentioned. That is, the clip 11 has a lead-in onto the sheet tapered or crimped end 43 which can be held together by the user's fingers while he slides the clip 11 onto the sheet portion 16 and along the holder upturned end 18. With this arrangement, the clip 11 can be of a minimum span between its legs 36, to tightly hold the sheet, but it will be able to be slid readily onto the clamping or holding position by virtue of the lead-in given by the sheet tapered portion 43 formed by the squeezing of the user's fingers to form the portion 43 as shown in FIG. 6.

FIG. 5 shows that the platen sections can be angled slightly upwardly, as shown by the sections designated 44 and 46 in FIG. 5, such that when the handle portion 24 is squeezed together the sections 44 and 46 will come into a plane relative to each other so that upon release of the squeezing of the handle 24 the platen sections 44 and 46 may occupy the same flat plane in the event the handle portion 24 does not return to its full line position shown in FIGS. 1 and 5. That is, with the arrangement shown in FIG. 5 and with the slightly upturned platen sections 44 and 46, in the final assembly with the sheet 12, the platen portions 44 and 46 may occupy the same plane in an arrangement where the handle portions 39 and 41 remain at least closer to the dotted positions, rather than the solid line positions, shown in FIG. 5. Depending upon tautness desired in the sheet 12, and upon the degree of resiliency in the handle portion 24, the arrangement of FIG. 5 may be employed, if desired.

The body piece 10 can therefore be made of one continuous sheet form extending from one leg or end 17 through to the other leg or end 18, and the sheet can be of any length of say many feet made in an extrusion process to give it the configuration seen in FIG. 1. Then the long extruded sheet can be cut into desired lengths, of say six or so inches, and thus a number of body pieces 10 can be made from one extruded long sheet. Likewise, the clips 11 can be made from one extruded long sheet and can be cut to the same lengths as the length of the body piece 10, as described. As further mentioned, the clips 11 extend throughout the length of the body piece, so the sheet is held firmly along the entire length of the body piece 10. Of course the clips 11 have their opposite ends open so that they can slide over the sheet and over the upturned ends 17 and 18 in either direction and axially of the length of the clips 11.

It will therefore be seen and understood that the holder of this invention is of a simplified construction which permits ready and easy attachment and/or replacement of the sheet, and which holds the sheet in a taut manner. Further, the sheet may be of any material, such as cloth, fleece, paper, or the like, and it can be used for any purpose of applying paint, liquid, sandpapering, or the like. One particular application of this holder is for the purpose of applying development liquids to a photolithographic plate, and here it will be understood that the sheet 12 is preferably of a fleece material and extends beyond the edges of the holder itself so that the holder is not exposed to the delicate plate and therefore cannot scratch or damage the plate. Also, the solvents of the development liquid commonly

damage the sheets which are used for applying the liquid so that the sheets have to be frequently replaced, and this holder permits such easy and ready replacement. Still further, the holder of this invention is susceptible to receiving different colorings or like markings or indicia so that a holder made of one color, say of one plastic material having a color, can be used for applying one liquid to a plate, and then a holder of a different color can be readily provided and used for applying another liquid to the same plate, and in these applications, the user will not be interchanging the liquid and the applicator or holder and will therefore not make a mistake and inadvertently apply the wrong holder to the plate having a certain developer or solvent applied to it. The fact that the configuration of this holder lends itself to formation by an extruding process renders the provision of the different colored holders a constructive and feasible provision, such as for the purpose mentioned. At the same time, the holder is of a lightweight and has no hinged parts, nails or staples or the like which could possibly damage the work surface, such as a sensitive photolithographic plate, and the holder is arranged with the handle 24 having its inclined legs 26 so that the user can securely and accurately hold and direct and position the entire holder in its use.

Further, the holder 10 is susceptible to being made of a flexible material, such as a plastic material, for the purpose of positioning it in the dotted line position shown and described in connection with FIG. 5, and also for the purpose of permitting the user to press down onto a work surface and thereby apply only one corner or one side, such as either platen section 21 or 22, to the work surface. That is, the user can hold the handle 24 and press down onto the work surface to have only one corner of either platen section 21 or 22 bear down against the work surface, and the platen sections 21 or 22 will sufficiently flex so that only the corner thereof will be down on the work surface. Alternatively, the user can bear downwardly onto the work surface to have either the entire platen section 21 or 22 apply to the work surface, rather than only one corner thereof. The feature of having only a corner of the entire holder apply to the work surface is important where it is desired to have only a small part of the entire platen applied to the work surface or to have a specific pressure of application of the platen apply to the work surface.

What is claimed is:

1. A releasable sheet holder comprising a body piece of generally a W shape, a platen portion included in said body piece and extending throughout the area of said body piece at one side thereof and having a face for presenting a backing support for a sheet lying across said platen portion, the two ends of said body piece at opposite sides thereof being upturned ends extending offset from the plane of said face to present the two outer legs of the W shape and to engage the opposite ends of a sheet which is extending across said platen and is draped over said two ends, a handle portion included in said body piece and extending centrally thereon to present the center section of the W shape, and a U-shaped clip releasably disposed on each of said two legs and being positionable over the respective opposite draped ends of the sheet for holding the sheet to said body piece.

2. The releasable sheet holder as claimed in claim 1, wherein said platen portion consists of two spaced-apart sections, said handle portion being connected to said platen sections and being resilient for yieldingly urging said platen sections away from each other, whereby said platen sections can be moved toward each other while the sheet is disposed across said platen portion and said platen sections subsequently tautly dispose the sheet across said platen portion when the sheet is being held by said body piece and said handle is urging said platen sections away from each other.

3. The releasable sheet holder as claimed in claim 2, wherein said body piece is a one-piece member and said handle portion is in a loop configuration extending continuously from one of said platen sections to the other of said platen sections.

4. The releasable sheet holder as claimed in claim 1, wherein said body piece is a one-piece member extending continuously in sheet form from one of said legs to the other of said legs and including said handle portion which is disposed in the form of a loop of said sheet form.

5. The releasable sheet holder as claimed in claim 4, wherein said platen portion consists of two spaced-apart sections, and said handle portion is between said platen sections.

6. The releasable sheet holder as claimed in claim 5, wherein said platen sections are spaced apart by said handle portion, and said handle portion is resilient for moving said platen sections toward each other for tautly attaching the sheet to said body piece.

7. The releasable sheet holder as claimed in claim 4 wherein said body piece is of the one-piece and sheet form suitable for forming by extrusion from resilient plastic material.

8. The releasable sheet holder as claimed in claim 1, wherein said legs have enlarged portions on the extending edges thereof for snugly receiving said clips.

9. The releasable sheet holder as claimed in claim 1, wherein the length of said body piece in the direction along the terminal edges of said upturned ends and the length of said clips in the direction along said terminal edges are equal to each other.

10. The releasable sheet holder as claimed in claim 1, wherein said clips have an open end for sliding onto said upturned ends, and the length of said body piece in the direction along the terminal edges of said upturned ends is less than the length of the sheet being held by said holder, and said sheet overlaps the edge of said upturned ends in the direction of the length of said body piece, for crimping the overlapped end of said sheet to facilitate sliding said clips onto said upturned ends and over said sheet.

11. The releasable sheet holder as claimed in claim 1, wherein said body piece is made of a resilient plastic material for flexing of said platen portion when applied to a work surface for applying only a corner of said platen portion to the work surface.

12. The releasable sheet holder as claimed in claim 11, wherein said platen portion is in two spaced-apart platen sections, and said handle portion is in a loop configuration connecting said platen sections together whereby either one of said platen sections can be pressed against a work surface while said handle portion is flexed to hold the other of said platen sections off the work surface.
